UNITED STATES PATENT OFFICE.

CHARLES J. BAILEY, OF NEWTON, MASSACHUSETTS.

DESIGN FOR AN OVERSHOE.

SPECIFICATION forming part of Design No. 31,217, dated July 11, 1899.

Application filed June 15, 1899. Serial No. 720,708. Term of patent 7 years.

To all whom it may concern:

Be it known that I, CHARLES J. BAILEY, a citizen of the United States, residing at Newton, in the county of Middlesex and State of Massachusetts, have invented and produced a new and useful Design for an Overshoe, of which the following is a description, reference being had to the accompanying drawings, forming a part thereof.

Figure 1, in side elevation, represents an overshoe illustrating my design; and Fig. 2 is an end elevation of the shoe shown in Fig. 1.

The leading feature of my design for an overshoe consists in a multiplicity of projections or nubs at the heel end of the shoe and extended upwardly from at or near the sole thereof.

The overshoe has the rear part of its heel end A provided with a multiplicity of projections or nubs *a*, extended upwardly from at or near the sole *b* of the shoe.

Having fully described my design, what I claim is—

The design for an overshoe, substantially as herein shown and described.

In testimony whereof I have signed my name to this specification in the presence of two subscribing witnesses.

CHARLES J. BAILEY.
